RAZOR BLADE SHARPENER

Walter Ward Skerry, New York, N. Y.

Application July 3, 1935, Serial No. 29,615

3 Claims. (CL. 51—86)

This invention relates to new and useful improvements in a razor blade sharpener.

The invention has for an object the construction of a device as mentioned which is characterized by a casing having an opening in one side through which a slide may be extended, and upon which a razor blade may be secured, an arrangement wherein the slide may be pushed back into the casing, and mechanism operable to cause the sharpening of the blade.

More particularly, it is proposed to have the mechanism spring operated with a winding stem on the outside of the casing.

Still further it is proposed to characterize the mechanism by superimposed pairs of spaced sharpening rollers, and a mechanism for oscillating the blade so that it comes in contact with the sharpening rollers.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a razor blade sharpener constructed according to this invention.

Fig. 2 is a transverse sectional view as though taken on the line 2—2 of Fig. 3.

Fig. 3 is a sectional view taken on the line 3—3 of Fig. 2.

Fig. 4 is a fragmentary sectional view taken on the line 4—4 of Fig. 3.

Fig. 5 is a sectional view of the spring motor of the device.

The razor blade sharpener, according to this invention, includes a casing 10 substantially of clock shape and formed with a side opening 10^a through which a slide 11 is extendable. A razor blade 12 is adapted to be mounted upon this slide so that when the slide is moved to its retracted position the blade is within the casing. The slide 11 is mounted upon a pivoted carriage 13. A pintle pin 14 serves to pivotally connect the carriage 13 upon a bracket 15 attached on the side of the casing.

Four parallel sharpening rollers arranged in superimposed pairs 16 and 16' spaced from each other are associated with a spring motor to cause

their rotation and thus their operative sharpening condition. The blade 12 is adapted to be engaged against the sides of these rollers as hereinafter more fully explained.

The spring motor comprises a hollow drum 17 having one side open and rotatively supported coaxially on its closed side by a stud 18 upon the casing 10. A disc 19 closes the open side of the drum 17. A spring 20 is housed within the drum and has its outer end attached upon the drum, and its inner end attached upon a coaxial winding stem 21. This winding stem is equipped with a bevel gear 22 which meshes with a bevel gear 23 upon a stem 24 which projects to the exterior of the casing. A wing headed member 25 is secured upon the outer end of the stem 24 by which the spring motor may be wound. During the process of winding the device the resilient arm 40 must be in an operative position to hold the drum 17 in an inoperative position.

The drum 17 is formed with a flange 17' upon which there are gear teeth 26. These gear teeth mesh with gears 27 rotatively supported and coaxially connected with pinions 28, which in turn mesh with gears 29 upon one of the axles of each of the pairs of sharpening rollers. The gears 29 mesh with gears 30 on the other of the sharpening rollers. The arrangement is such that when the drum 17 rotates each pair of sharpening rollers will be rotated.

A mechanism is provided for operating the carriage to lightly engage the edges of the blade against the sharpening rollers. This mechanism consists of a pinion 31 also meshing with the gear teeth 26 and fixed upon a rotatively supported shaft 32 which is equipped with a toothed wheel 33. The carriage 13 has a downward projecting stem 13^a which engages the teeth of the wheel 33. The pintle 14 is engaged through the stem 13 for the pivotal supporting of the carriage. A spring 34 acts between the stem 13^a and the casing 10 to normally pivot the carriage in one direction. When the toothed wheel 33 turns each tooth will pivot the carriage for a short distance in the other direction. When this particular tooth releases the stem 13^a, the spring 34 will draw the stem back to its original position and thus the carriage is caused to oscillate.

The slide 11 is adapted to support the blade 12 and has several headed screws 36 engaged through openings in the blade for fixedly mounting the blade on the slide. At the inner end the slide 11 has outwardly projecting arms 37 which support members 38 adapted to engage in between the pairs of the rollers when the slide is

5 moved into the extended position so as to center the blade 12 between the pairs of rollers and prevent the blade from cutting the rollers during the motion of the slide in and out from the casing. As shown in Fig. 2, the slide 11 is slightly extended to illustrate the members 38 between the sharpening rollers so that the blade 12 is out of contact with the rollers.

10 A mechanism is provided for normally latching the spring motor against operation. This mechanism consists of an arm 40 attached at one end 41 upon the casing on the side opposed to the opening 10^a and extending substantially to the vicinity of the opening 10^a. This arm 40 has several branch fingers such as upwardly projecting fingers 42 which normally engage the teeth of gears 43 coaxially fixed on the lowermost rollers of each pair of rollers. Thus, the rollers are held against rotation.

15 20 A branch arm 44 from the arm 40 extends through a vertical slot 45 in the casing and the extended end has a head 46 by which it may be moved. When the head 46 is moved downwards along the slot 45 the arm 40 will be flexed and the fingers 42 will be moved out of contact with the gears 43 to release the spring motor. The slot 45 has transverse branches 45^a and 45^b at the top and bottom, respectively, into which the branch 44 automatically tends to engage due to its resiliency so that the arm 40 will be locked in one or the other position.

25 30 A means is also provided for preventing the release of the spring motor when the slide 11 is extended and for latching the slide in its retracted position when the spring motor is released. This means consists in several additional branch fingers 49 from the arm 40 and having down-turned ends (see Fig. 3) which are adapted to engage in transversely elongated openings 50 in the slide. It is only in the retracted position of the slide that the openings are in the proper positions to receive the ends of the branches 49. When the slide is extended it is impossible to move the arm 40 downwards because of the branches 49. Thus, 35 the spring motor must remain inoperative. It is only when the slide is retracted that the arm 40 may be moved downward. Then the slide is locked in the retracted position and the spring motor is freed to operate.

40 45 50 The operation of the spring motor consists in the drum 17 rotating and the teeth 26 transmitting its rotation to the gear 31 and the pinions 27. The pinions serve to transmit the rotations of the drum to the train of gears which rotate the sharpening elements. The gear 31 transmits the rotation of the drum 17 to oscillate the carriage 13. One cycle of oscillation of the carriage consists in the carriage pivoting in one direction so that the blade engages the lowermost roller of one of the pairs of rollers, and simultaneously, the uppermost roller of the other of the pairs of rollers. Then, as the carriage pivots in the opposite direction the blade will engage the lowermost roller of the latter-mentioned pair of rollers, and the uppermost roller of the first mentioned pair of rollers. Thus, both edges and both sides of the edges of the blade are sharpened.

55 60 65 It is to be understood that the size and shape of the device may be changed as desired and that the stropping rollers may be of any suitable material and construction.

70 While I have illustrated and described the preferred embodiment of my invention, it is to be

understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a razor blade sharpener, four parallel sharpening rollers arranged in superimposed pairs spaced from each other and rotative within a casing, a pivoted carriage between said pairs of rollers, a slide extendably mounted on the carriage and from the casing and adapted to hold a razor blade with its edges engageable against said rollers during the retracted position of the slide while the slide oscillates, a spring mechanism normally held inoperative and adapted to rotate said rollers, oscillating means for the carriage connected with said spring mechanism, a resilient arm supported on the casing and having branches engaging elements of the spring operated motor to normally hold the motor in an inoperative position, means for latching the carriage in a retracted position and simultaneously flexing said arm for releasing the spring motor mechanism said means for latching the carriage including fingers from said arm engageable in aligned openings in the slide in the retracted position thereof, said aligned openings being elongated so as not to interfere with the oscillation of the carriage. 20

2. In a razor blade sharpener, four parallel sharpening rollers arranged in superimposed pairs spaced from each other and rotative within a casing having a slot therein, a pivoted carriage between said pairs of rollers, a slide extendably mounted on the carriage and from the casing and adapted to hold a razor blade with its edges engageable against said rollers during the retracted position of the slide while the carriage 40 oscillates, a spring mechanism adapted to rotate said rollers, oscillating means for the carriage connected with said spring mechanism, gears on the end of one of said pairs of rollers, and a resilient arm supported on the casing and having 45 branches engaging the teeth of said gear to normally hold the motor in an inoperative position, and a branch arm engaging said slot and mounted on said resilient arm to control the operation of said arm. 50

3. In a razor blade sharpener, four parallel sharpening rollers arranged in superimposed pairs spaced from each other and rotative within a casing having a slot therein, a pivoted carriage between said pairs of rollers, a slide extendably mounted on the carriage and from the casing and adapted to hold a razor blade with its edges engageable against said rollers during the retracted position of the slide while the carriage oscillates, a spring mechanism adapted to rotate 60 said rollers, oscillating means for the carriage connected with said spring mechanism, gears on the end of one of said pairs of rollers, and a resilient arm supported on the casing and having 65 branches engaging the teeth of said gear to normally hold the motor in an inoperative position, and a branch arm engaging said slot and mounted on said resilient arm to control the operation of said arm, said means for latching the carriage including fingers from said arm engageable in aligned openings in the slide in the retracted position thereof. 70
